UNITED STATES PATENT OFFICE

160,145

COIN CONTROLLED INSURANCE POLICY VENDING MACHINE

Ralph W. Brown, Columbus, Ohio

Application June 23, 1949, Serial No. 3,463

Term of patent 14 years

(Cl. D52—3)

To all whom it may concern:

Be it known that I, Ralph W. Brown, a citizen of the United States, residing at Columbus, in the county of Franklin and State of Ohio, have invented a new, original, and ornamental Design for a Coin Controlled Insurance Policy Vending Machine, of which the following is a specification, reference being had to the accompanying drawing, forming part thereof;

In the drawing, Figure I is a perspective view of a coin controlled insurance policy vending machine showing my new design, the dotted lines showing a separate extension on the top;

I claim:

The ornamental design for a coin controlled insurance policy vending machine, substantially as shown and described.

RALPH W. BROWN.
